(57) **CLAIM**

The ornamental design for a controller with removable paddles, as shown and described.

DESCRIPTION

FIG. 1 is a rear perspective view of a controller with removable paddles showing our new design in a first, configured state;

FIG. 2 is a bottom view thereof;

FIG. 3 is a rear view thereof;

FIG. 4 is a front view thereof;

FIG. 5 is a right side view thereof;

FIG. 6 is a left side view thereof;

FIG. 7 is a top view thereof;

FIG. 8 is an exploded rear perspective view of a controller with removable paddles, shown in a second unconfigured state;

FIG. 9 is an exploded bottom view of FIG. 8;

FIG. 10 is an exploded rear view of FIG. 8;

FIG. 11 is an exploded front view of FIG. 8;

FIG. 12 is an exploded right side view of FIG. 8;

FIG. 13 is an exploded left side view of FIG. 8; and,

FIG. 14 is an exploded top view of FIG. 8.

The broken lines adjacent to the shade lines define the bounds of the claim. Other broken lines are shown for environmental purpose only. None of the broken lines form part of the claimed design.
